UNITED STATES PATENT OFFICE

2,507,293

WATER TUBE COIL STEAM GENERATING APPARATUS

Perry Arant, Alhambra, Calif., assignor to Clayton Manufacturing Company, Alhambra, Calif., a corporation of California

Application January 22, 1947, Serial No. 723,524

7 Claims. (Cl. 122—250)

1

The present invention relates to steam generating apparatus and more particularly to a steam generating coil for use in such apparatus.

More specifically, the steam generating coil of the present invention comprises a double wound water wall section including two interwound upright helical pipe coils extending for substantially the full height of the steam generating unit, and a steam generating or main heating section comprising two groups of pancake-type pipe coils connected in series and arranged within the water wall section and extending downwardly therein to a zone substantially medially of the height of said water wall section. The double wound water wall section may be made by the method disclosed and claimed in my co-pending application Serial No. 688,720, filed on August 6, 1946, and entitled "Heating coil and method of making same." The space within the water wall section below the pancake coils provides a combustion chamber whose side wall is lined with a sheet metal liner of the kind disclosed and claimed in my co-pending application Serial No. 688,721, filed on August 6, 1946, and entitled "Steam generating apparatus."

The principal object of the invention is to provide a steam generating unit which is extremely compact, but nevertheless capable of developing a given high boiler horsepower without sacrificing efficiency and economy.

Another object of the invention is to provide a steam generating coil constructed so that it will prevent substantial local separation of the liquid and vapor within the coil, which, under certain conditions of operation, produces a thermal cycle or coil priming conducive to surging or spasmodic discharge from the coil.

Another object of the invention is to provide a steam generating coil constructed so as to minimize friction flow losses as the liquid is expanded by heat, and as the result of the presence of some vapor in the liquid, as the liquid approaches the discharge end of said coil.

Still another object of the invention is to provide a steam generating coil including a water wall section arranged so that fluid can be discharged therefrom into the main heating section of said coil without the use of any external risers.

Other objects and advantages of the invention will be apparent from the following description taken in conjunction with the accompanying drawings, in which:

Fig. 1 is a longitudinal sectional view through a steam generating unit containing a coil embodying the principles of the present invention;

2

Fig. 2 is a fragmentary perspective view of the upper portion of the water wall section of the coil; and

Fig. 3 is a perspective view of the lower portion of the water wall section of the coil, particularly illustrating the return bend connection for establishing reverse flow of fluid through said water wall section.

Referring now more particularly to Fig. 1 of the drawings, the numeral 1 generally identifies the steam generating unit, which includes a housing 2 made up of a base 3, jacket or casing sections 4 and 4^a, and a top 5, all secured together in any suitable or conventional manner. The housing 2 is supported by a plurality of legs 6 disposed below the base 3.

The base 3 includes a wall 7 provided with a central air opening 8 through which the upper end of a burner or fuel supply device 9 is adapted to extend. An air supply duct 10 is disposed below the wall 7 and is arranged to deliver air from a blower (not shown) to an air supply chamber 11 surrounding the fuel supply device 9.

The base 3 includes a wall 12 spaced from the wall 7 by a plurality of air deflecting baffles 13, the arrangement of which is unimportant for the present disclosure, but which is set forth in detail in my co-pending application Serial No. 688,720, supra. The wall 12 is provided with a central opening 14 having an annular bushing 15 mounted therein. The opening in the bushing 15 is concentric with the opening 8 and establishes communication between the air supply chamber 11 and a combustion chamber 16 within the casing 4. A ring 17 is welded or otherwise secured to the wall 12 and the portion of said wall between said ring and the bushing 15 is lined with suitable refractory material 18 serving as the bottom of the combustion chamber 16.

The fuel supply device 9 includes a pair of fuel oil atomizing nozzles 19 for introducing atomized fuel into the combustion chamber 16. A pipe 20 is connected to the device 9 for supplying fuel thereto, and electrode means 21 is arranged adjacent the nozzles 19 to ignite the atomized fuel. It will be understood, of course, that air to support combustion is supplied to the combustion chamber 16 simultaneously with the supply of fuel, through the air duct 10, supply chamber 11, etc.

The steam generating coil is generally identified by the numeral 22 and includes a double wound water wall section 23 preferably consisting of two predetermined lengths of helical pipe 24 and 25 interconnected at their lower ends

by a generally U-shaped return bend 26. The method of winding a double coil similar to the water wall section 23 is set forth in my copending application Serial No. 688,720, supra.

The steam generating coil 22 also includes a steam generating or main heating section 23^a disposed within the water wall section 23 and comprising two groups of spirally wound pancake-type pipe coils generally identified by the numerals 27 and 28, respectively, the first or upper group of pancake coils 27 consisting of, for example, eight pancake sections and having a depth indicated by the dimension A, and the second or lower group of pancake coils 28 consisting of, for example, five pancake sections and having a depth indicated by the dimension B. The pipe wound to form the pancake coils 28 is larger in diameter than that employed in the pancake coils 27, for reasons explained later. The combined depth of the two groups of coils, as indicated by the dimensions A and B, is approximately equal to half the height of the water wall section 23.

The upper end 29 of the helical coil 24 of the water wall section 23 serves as an inlet and has a water supply pipe 30 connected thereto. The upper end 31 of the other helical pipe 25 of the water wall section 23 is connected to the inlet end 32 of the top pancake coil 27 of the group of coils occupying the space dimensioned A. All of the pancake coils 27 are connected for series flow of fluid therethrough, and the outlet end 33 of the lowermost pancake coil 27 is connected with the inlet end 34 of the uppermost pancake coil 28. All of the pancake coils 28 of the group occupying the space dimensioned B are also connected for series flow of the fluid therethrough, and the outlet end 35 of the bottom pancake coil 28 is connected to one end 36 of a discharge conduit 37, which extends upwardly through the core of the entire stack of pancake coils constituting the heating section 23^a. A discharge pipe 38 is connected with the upper end of the discharge conduit 37.

In constructing the steam generating coil 22, the pipes 24 and 25 of the water wall section 23 are wound in helical form in such manner that the adjacent coils preferably contact each other. The pancake coils 27 and 28 are preassembled and connected in series and the uppermost pancake coil 27 is welded to supporting bars 39 having a loop 40 secured thereto to enable the assembly to be handled by a crane and lowered into nesting position within the water wall section 23. The outlet 31 of the water wall section 23 and the inlet 32 of the top pancake coil 27 of the heating section 23^a are welded together after these sections are nested. Brackets 41 secure the ends of the bars 39 to an upper shell section 42 which partially overlaps the upper end of the casing 4 and is welded thereto. The casing sections 4 and 42 are surrounded by suitable heat insulating material 43.

All of the pancake coils 27 and 28 of the heating section 23^a are spaced apart vertically to permit the free flow of the hot gases of combustion thereover, baffles 44 being arranged at the lower portion of said heating section to prevent the direct passage of the combustion gases from the combustion chamber 16 through the core formed at the central portion of said heating section. A stack 45 is connected with the top 5 of the housing 2 above said core.

A stainless steel sheet metal liner 46 of the character described in detail in my co-pending

application, Serial No. 688,721, supra, is disposed in the combustion chamber 16 in telescopic relation with the ring 17, and extends from the wall 12 to a zone occupied by the lowermost pancake coil 28 of the heating section 23^a.

The liner 46 has its outer periphery in contact with the inner surface of the surrounding coils of the water wall section 23 and serves as a side wall for the combustion chamber 16. The liner 46 conducts heat directly to approximately the lower half of the water wall section 23 in contact therewith, the heat being rapidly transferred to the liquid in the water wall section 23 at a rate sufficient to prevent burning out or undue heating of the liner 46.

The operation of the steam generating unit 1 is as follows:

The liquid to be heated is supplied through the pipe 30 to the inlet end 29 of the helical pipe 24 of the water wall section 23 and said liquid flows downwardly through the coils provided by said pipe. The direction of flow of the liquid through the water wall section 23 is reversed at the return bend 26 and then flows upwardly through the coils of the helical pipe 25 and ultimately discharges through the outlet end 31 thereof into the inlet end 32 of the top pancake coil 27 of the main heating section 23^a. The construction of the water wall section 23 and the liner 46 is such that a substantial amount of heat is absorbed by the liquid in the water wall section 23 so that it is preheated before it enters the top pancake coil 27. By virtue of the dual helical coil arrangement in the water wall section 23, it will be apparent that the direction of flow of the fluid is opposite in any two adjacent coils thereof, and also that the incoming fluid in the coil 24 travels in a direction counter to that of the flow of the combustion gases while the fluid flow in the coil 25 is in the same direction as that of the gases. However, the flow of the fluid is again reversed when it enters the pancake coils of the main heating section 23^a. In other words, the direction of flow of fluid through the pancake coils 27 and 28 is counter to that of the travel of the gases of combustion, with the result that the fluid in said heating section is subjected to the hottest gases in the combustion chamber 16 just prior to its entry into the discharge conduit 37.

It will be noted from Fig. 1 that the diameter of the pipe employed in making the upper group of pancake coils 27 is of the same size as the pipe in the water wall section 23, and that the pipe employed in making the lower group of pancake coils 28 is larger than that of the pipe employed in making said water wall and upper group of pancake coils. As an example of one operative embodiment of the present invention, a 100 horsepower boiler preferably employs pipe 1 inch

in diameter for making the water wall section 23 and the upper group of pancake coils 27, whereas the diameter of the pipe employed in making the lower group of pancake coils 28 is preferably 1½ inches. The object of making the pancake coils 28 of larger diameter pipe is to provide additional space or volume at the outlet end of the heating section 23^a to compensate for the thermal expansion of the liquid and for the presence of vapor in said liquid, to thereby reduce losses due to friction flow, and to avoid the collection of vapor in "slugs," which are jointly conducive to retarded flow and cause non-uniform or spasmodic discharge of the fluid from the unit.

It will be understood that both the water wall section 23 and the main heating section 23^a may

include as many coils as are necessary to meet the requirements of a desired installation, and that the particular number of coils shown in the drawings and mentioned in the specification is merely by way of illustration of one operative embodiment of the invention and not by way of limitation.

It will also be understood that various changes may be made in the construction and arrangement of the parts comprising the present steam generating unit without departing from the spirit of the invention or the scope of the annexed claims.

I claim:

1. A heating coil, comprising: a water wall section including two upright helical coils of pipe having their turns intermeshed and their lower ends interconnected by a return bend, the upper end of one of said helical coils serving as an inlet; a heating section including a plurality of spirally wound, superposed pancake-type pipe coils connected in series, the upper end of the other helical coil of said water wall section being connected to the top pancake coil of said heating section; and a discharge conduit connected to the bottom pancake coil of said heating section.

2. A heating coil, comprising: a water wall section including two upright helical coils of pipe having their turns intermeshed and their lower ends interconnected by a return bend, the upper end of one of said helical coils serving as an inlet; a heating section disposed within the upper portion of said water wall section and including a plurality of spirally wound, superposed pancake-type pipe coils connected in series, the upper end of the other helical coil of said water wall section being connected to the uppermost pancake coil of said heating section; and a discharge conduit connected to the lowermost of said pancake coils of said heating section.

3. A heating coil as defined in claim 2, in which the height of the pancake coil heating section is approximately half the height of the water wall section.

4. A heating coil, comprising: a water wall section including two upright helical coils of pipe having their turns intermeshed and their lower ends interconnected by a return bend, the upper end of one of said helical coils serving as an inlet; a heating section disposed within the upper portion of said water wall section and including an upper group and a lower group of spirally wound, superposed pancake-type coils connected in series, the upper end of the other helical coil of said water wall section being connected to the top pancake coil of said upper group of pancake coils, the lower group of pancake coils consisting of pipe of a larger diameter than that of the upper group of pancake coils to compensate for expansion of the liquid being heated and for the presence of vapor therein and thereby avoid surging or spasmodic discharge therefrom; and a discharge conduit connected to the bottom pancake coil of said lower group of pancake coils.

5. Steam generating apparatus, comprising: a housing including a base, a side wall casing, and a top; and a steam generating coil comprising a double wound water wall section having an inlet and an outlet at the upper end thereof, said water wall section being disposed within said casing and extending substantially for the full height of

said casing, and a heating section comprising a plurality of superposed pancake coils arranged within said water wall section and having the uppermost pancake coil thereof connected to the outlet of said water wall section, the lowermost pancake coil being spaced from said base to provide a combustion chamber.

6. Steam generating apparatus, comprising: a housing including a base, a side wall casing, and a top; a steam generating coil comprising a double wound water wall section having an inlet and an outlet at the upper end thereof, said water wall section being disposed within said casing and extending substantially for the full height of said casing, and a heating section comprising a plurality of superposed pancake coils arranged within said water wall section and having the uppermost pancake coil thereof connected to the outlet of said water wall section, the lowermost pancake coil being spaced from said base to provide a combustion chamber, said base having an air inlet opening communicating with said combustion chamber; refractory material on said base surrounding said air inlet opening; and a heat conducting liner in said combustion chamber disposed between said refractory material and the lowermost pancake coil of said heating section and having its outer periphery in contact with said water wall section.

7. Steam generating apparatus, comprising: a housing including a base, a side wall casing, and a top; a steam generating coil comprising a double wound water wall section having an inlet and an outlet at the upper end thereof, said water wall section being disposed within said casing and extending substantially for the full height of said casing, and a heating section comprising a plurality of superposed pancake coils arranged within said water wall section and extending downwardly into said water wall section to a zone substantially medially of the height of said water wall section to provide a combustion chamber below said heating section, said heating section having the uppermost pancake coil thereof connected to the outlet of said water wall section, said base having an air inlet opening communicating with said combustion chamber; refractory material on said base surrounding said air inlet opening; and a sheet metal liner in said combustion chamber disposed between said refractory material and the lowermost pancake coil of said heating section and having its outer periphery in contact with said water wall section.
